FIG. 4.

FIG. 5.

To all whom it may concern:

Be it known that I, Henry L. Heineke, residing in the city of Springfield, in the county of Sangamon and State of Illinois, have invented a new, original, and ornamental Design for a Power Lawn Mower, of which the following is a specification, reference being had to the accompanying drawing forming a part thereof.

Fig. 1 is a top plan view of a power lawn mower embodying my new design.

Fig. 2 is a side elevation thereof.

Fig. 3 is a front elevation of the carriage of the mower.

Fig. 4 is a bottom plan view of the carriage of the mower.

Fig. 5 is a rear elevational view of the carriage.

Fig. 6 is a perspective of the mower, looking at the front right corner.

The characteristic features of the design reside in the portions shown in full lines.

I claim:

The ornamental design for a power lawn mower, substantially as shown and described.
